Attest.

UNITED STATES PATENT OFFICE.

IRVING W. GIESE, OF CHICAGO, ILLINOIS.

MUSIC RACK.

Application filed August 16, 1926. Serial No. 129,381.

My invention relates to improvements in music racks, and has more particular reference to music racks such as are commonly provided on pianos.

5 One object of my invention is to provide an auxiliary music rack of new and improved construction which may be moved down into position over the piano keyboard so as to assist children and near-sighted persons in 10 reading the music placed upon the rack.

Another object of the invention is to provide a music rack which is hinged to the ordinary rack of a piano in such a way that it will be concealed behind the ordinary rack 15 when not in use. The invention is particularly adapted for use on grand pianos wherein the ordinary music rack is usually hinged at its lower edge to a slideable carriage which may be moved back and forth on the piano 20 frame.

Other objects and advantages of the invention will become apparent from the following detailed description taken in connection with the accompanying drawings, in which:

25 Figure 1 is a front elevational view of a grand piano equipped with a music rack embodying the features of the present invention.

Figs. 2 and 3 are side views of the piano showing the music rack and its mounting in 30 vertical section.

Figs. 4 and 5 are fragmentary views showing details of the hinge employed in carrying out my invention.

While I have shown in the drawings, and 35 will herein describe, the preferred embodiment of my invention, it is to be understood that I do not intend thereby to be limited to the particular form disclosed, but aim to cover all modifications and alternative constructions 40 falling within the spirit and scope of the invention as expressed in the appended claims.

Referring now to the exemplary embodiment of the invention, the numeral 10 represents the frame of a grand piano supported 45 in the usual way by legs 11. The frame includes two side walls 12 between which extends a keyboard 13. Slidably mounted upon the piano frame behind and substantially 50 above the keyboard is a carriage herein shown as comprising two spaced parallel cross pieces 15 and 16 suitably connected at their opposite ends.

The ordinary music rack for the piano 55 comprises a flat board 17 pivotally mounted at its lower edge on the front cross piece 15.

For this purpose, hinges 18 are fastened on the cross piece 15 at its rear edge and are secured to the front face of the board 17 a short distance above its lower edge. Thus, the 60 rear movement of the rack will be limited by the rear edge of the cross piece 15 when the rack is swung back into normal supporting position as shown in Fig. 3. When it is desired to close the piano, the rack 17 may be 65 swung down upon the frame as shown in Fig. 2.

The auxiliary rack which constitutes an important part of the present invention, comprises a board 19 hinged at one edge to the 70 free edge of the rack 17 and provided at its opposite edge with a flange 20 for supporting sheets of music. Preferably a double hinge construction of the type shown in Figs. 4 and 5 is employed for mounting the rack 19. 75 This hinge comprises two end members 21 and 22 having eyes 23 spaced apart so as to receive eyes 24 on opposite ends of an intermediate member 25, the three members being united in the usual way by pintles 26. In 80 the present instance, the hinge member 21 is secured to the upper edge of the rack 17 so that the member 25 will have a limited movement in a clockwise direction due to engagement with the member 21 (Fig. 4). The 85 member 22 is secured to the rear face of the board 19 and its movement in a clockwise direction is limited by lugs 27 positioned to engage the member 25 (Fig. 4).

When it is desired to use the auxiliary rack 90 for supporting music, the rack 17 is swung downwardly upon the piano frame as shown in Fig. 2. Then, the auxiliary rack 19 is swung forwardly and downwardly into the position shown in Fig. 2, the hinge members 95 being then in their limiting positions so as to support the rack. In this position the rack 19 is disposed directly above the piano keyboard and in front of the part 20^a which is commonly called the fall board of the piano 100 and which defines a vertical wall along the rear edge of the keyboard 13. Thus, the music rack may be supported relatively close to the pianist and its lower edge will be disposed at such height above the keyboard as 105 to permit convenient manipulation of the keys.

When the rack 17 is to be used for supporting music, the rack 19 is swung backwardly into the position shown in Fig. 3, the flanged 110 edge being then disposed in the space between the cross pieces 15 and 16. In this position

the auxiliary rack will be concealed behind the rack 17.

It will be apparent that the music rack thus provided will materially aid children and near-sighted persons in reading the music. The rack is simple and inexpensive in construction, and neat and artistic in appearance.

I claim as my invention:

1. The combination with a grand piano, of 10 a carriage slidably mounted on the piano frame, a board hinged to said carriage and constituting a music rack, and an auxiliary music rack hinged to the free edge of said board and adapted to be swung downwardly 15 into position above the piano keyboard so as to constitute a secondary support for music.
2. The combination with a grand piano, of 20 a carriage mounted to slide back and forth on the piano frame, said carriage having two parallel cross pieces, a board hinged to the forward cross piece and constituting a music rack, a second board hinged to the free edge of said first mentioned board and constituting 25 an auxiliary music support, the free end of said second board being adapted to project into the space between said cross pieces when said first mentioned music rack is in use.
3. The combination with a grand piano, 30 having a frame, of a board pivotally mounted on said frame and constituting a support for music when in upright position, an auxiliary music rack hinged on said board and arranged to be swung downwardly into position above the piano keyboard for supporting music 35 thereon, said auxiliary rack being swung rearwardly and concealed behind said board while the board is being used for supporting the music.
4. The combination with a piano having a 40 music rack hinged thereto, of an auxiliary music rack hinged to said first mentioned rack and arranged to be swung downwardly into position above the piano keyboard to provide a secondary support for music.
5. The combination with a music rack, of 45 an auxiliary music supporting rack having a double hinge connection with said first mentioned rack.
6. The combination with a swingable music 50 rack, of an auxiliary music rack, and a hinge connecting said racks, said hinge comprising three members linked together, one of the end member of said hinge being secured to each of said rack.

7. The combination with a music rack, of a 55 member pivotally connected to said rack and constituting an auxiliary support for music, and means for limiting the pivotal movement of said member in one direction.

8. The combination with a music rack, of 60 an auxiliary music rack, and a double hinge connecting said racks, said hinge comprising three members linked together, and means for limiting the movement of each end member of the hinge relative to the intermediate member of the hinge.

9. The combination with a grand piano, of 65 an auxiliary music rack pivotally mounted on the piano and adapted to be swung forwardly and downwardly into music supporting position 70 so as to overlie the piano keyboard.

10. An auxiliary music supporting rack for 75 a piano adapted to be secured to the ordinary rack provided on the piano and comprising a rectangular shaped member having a ledge for supporting music formed along one of its longitudinal edges, said member having means secured along its other longitudinal edge and adapted for attachment to said ordinary music rack so as to be supported by said 80 last mentioned rack.

11. An auxiliary music supporting rack for 85 a piano having a horizontal keyboard and a fall board defining a vertical wall along the rear edge of said keyboard comprising, in combination, a substantially flat member having a music supporting ledge, and means swingably supporting said member on the piano in inclined position directly above said keyboard and in front of said fall board with 90 said ledge disposed at such a distance above said keyboard as to allow for manipulation of the keys thereof.

12. An auxiliary music supporting rack 95 for a piano having a horizontal keyboard and a fall board defining a vertical wall along the rear edge of said keyboard comprising, in combination, a substantially flat member having a music supporting ledge and means for supporting said member in inclined position 100 directly above said keyboard and in front of said fall board with said ledge disposed at such a distance above said keyboard as to allow for manipulation of the keys thereof.

In testimony whereof, I have hereunto affixed my signature.

IRVING W. GIESE.
